TOY FIREARM

Martin L. Blumenthal, Summit, N.J., assignor to De Luxe
Reading Corp., Elizabeth, N.J., a corporation of New Jersey

Filed Mar. 15, 1965, Ser. No. 84,271

Term of patent 3½ years

(Cl. D34—15)

FIG. 1 is a right side elevational view of a toy firearm, showing my new design;

FIG. 2 is a left side elevational view of the firearm;

FIG. 3 is a top plan view of the firearm;

FIG. 4 is a bottom plan view of the firearm;

FIG. 5 is a front elevational view of the firearm;

FIG. 6 is a rear elevational view of the firearm.

The broken lines indicating bullets are for illustrative purposes only.

I claim:

The ornamental design for a toy firearm, substantially as shown and described.
